[57] CLAIM

The ornamental design for a abdominal feeding tube support, as shown.

DESCRIPTION

FIG. 1 is a front elevational view of the abdominal feeding tube support of the present invention;

FIG. 2 is a back elevational view of the abdominal feeding tube support of FIG. 1;

FIG. 3 is a left side elevational view of the abdominal feeding tube support of FIG. 1;

FIG. 4 is a right side elevational view of the abdominal feeding tube support of FIG. 1;

FIG. 5 is a top plan view of the abdominal feeding tube support of FIG. 1;

FIG. 6 is a bottom plan view of the abdominal feeding tube support of FIG. 1; and,

FIG. 7 is a top, front, right side perspective view of the abdominal feeding tube support of FIG. 1 in a closed position.
